GEORGE P. RASCK, OF DES MOINES, IOWA, ASSIGNOR TO JOHN DE WITT, OF KEOKUK, IOWA.

GEARING DEVICE.

1,087,980.

Specification of Letters Patent.

Patented Feb. 24, 1914.

Application filed December 14, 1912. Serial No. 736,857.

To all whom it may concern:

Be it known that I, GEORGE P. RASCK, a citizen of the United States, and resident of Des Moines, Iowa, have invented a certain new and useful Gearing Device, of which the following is a specification.

The object of my invention is to provide a gearing device of simple, durable and inexpensive construction, particularly adapted for use in connection with washing machines and wringers, and in which all of the parts are arranged to occupy a minimum of space.

A further object is to provide a gearing device for imparting a reverse motion to the wringer in which sliding keys and the like are not employed—to thereby add to the efficiency and longevity of the several pinions employed in my device.

A further object is to provide means whereby two or more pinions, on separate shafts, may be shifted at one and the same time by moving one lever.

A further object is to provide readily accessible means for operating the shifting means employed in the device.

These and other objects and advantages of my device will become readily apparent upon a further understanding of my invention.

My invention consists in the construction, combination and arrangement of the various parts of my device, whereby the objects contemplated are attained, as pointed out in my claims and illustrated in the accompanying drawings, in which:

Figure 1 shows a side elevation of a washing machine and wringer equipped with my invention, part of the gears and casing being broken away to show the construction;

Fig. 2 shows a detail sectional view of the gearing device attached to a wringer as viewed from the rear of the wringer; Fig. 3 shows a plan view of a portion of a washing machine equipped with my device, with the top of the gear casing removed; Fig. 4 shows a detail view of the means employed by me for connecting the pitman to the sector. Fig. 5 shows a detail view of the means employed for moving one of the shifting levers, and Fig. 6 shows a detail view of the manner in which the shifting rod is connected to the sliding pinions.

Referring to the accompanying drawings it will be seen that I have used the reference numeral "10" to designate the tub "11" the

wringer and "12" the wringer rolls, all of ordinary construction. Fixed to one end of the lower wringer shaft is a spur gear "13". Directly in line, in a lateral direction with this gear wheel, but on a separate shaft, is a similar spur gear "14", supported by a shaft mounted in a bearing on the casing "15". Arranged at points substantially equi-distant from the centers of the gears "13" and "14" and also substantially equi-distant from each other, are three small shafts, "16", "17", and "18" all rotatably mounted in the casing "15" near the bottom thereof. Mounted loosely on the shaft "16" is a sleeve "19" having formed at one end a wide pinion "21" and on the other a groove "20". Fixed to the shaft "17" and in mesh with the pinion "21" is a narrower pinion "22", slightly spaced apart from the pinion "21", and loosely mounted upon the same shaft "16" is another pinion "23", having formed at one side a groove "24" said groove being positioned exactly in line with the groove "20" on the first described pinion and sleeve.

In position between the grooves "20" and "24" with its end fitted into the said grooves, is a shifting bar "25" clearly shown in Fig. 6. In the exact center of the bar "25" is an opening into which is rigidly fitted a shifting rod "26", said rod extending outwardly through the side of the gear casing, and along the rear side of the wringer frame to the opposite end of the frame, for the purpose of shifting the pinions, as hereinafter described.

On the shaft "18" at its outward end is fixed a bevel gear "27" and on the same shaft, but on the interior of the casing is fixed a clutch member "28". Adjacent to this clutch member, and on the same shaft is a loosely mounted pinion "29" in mesh with the gear "14". At one side of the pinion "29" is a clutch member "30" co-acting with the member "28", and at the opposite side is a groove "31" into which is fitted a shifting bar "32", extending downwardly and rearwardly to the bottom of the casing, where it is provided with a sleeve "33" to receive a shifting rod "34", hereinafter described. A sleeve "35" is rigidly secured to the shaft "18" and fixed on one end thereof is a pinion "36", in mesh at all times with the pinion "22". On the opposite end of the sleeve is another pinion "37" in mesh with the

sliding pinion "23". All of the pinions on the third shaft are slightly larger in diameter than the other mentioned pinions for the purpose of effecting the proper speed. An 5 arm "38" formed integrally with the gear casing and extending outwardly from the lower side of the wringer frame has a bearing "39" formed at its outer end, and into this bearing is mounted a shaft "40". Said 10 shaft extends downwardly and forwardly along the side of the tub, where it is fitted into a bearing "41" on a platform "42". Fixed to the upper end of the shaft "40" is a beveled pinion "43" in mesh with the 15 gear "27". Near the lower end of the shaft is fixed a beveled gear "44" in mesh with a pinion "45", on a motor "46", which motor is preferably mounted on the platform "42".

20 Referring to Fig. 3, it will be seen that the dolly pitman "47" enters the casing through a slot "47a", and is connected at one end to the gear "14". This connection is effected by means of a pintle "48", fixed 25 to the spur gear "14", and a loop "49" mounted on the pintle, the ends of the said loop being fitted over the ends of the pitman, and there pivoted. The pitman at its outer end is connected to a sector "50" said 30 sector being pivoted near its center to a pin "51" rigidly secured to the cover. The periphery of the sector is provided with a set of teeth "52", in mesh with the pinion "53" on the dolly shaft.

35 It is of course important that the connection between the sector and pitman be made to permit the raising of the cover, and this result is accomplished in the following manner: The end of the pitman "47" is journaled to fit an opening in the loop "54" and held therein by means of a nut "55" or the like. At right angles to the pitman is a connecting member "56" also journaled 40 to enter the loop below the pitman and held 45 therein by means of a pin "57" or the like. The opposite end of the member "56" enters the forked end of the sector and is pivoted therein by means of a pin "58". This connection is best shown in Fig. 4.

50 It will be seen that power from the motor is transmitted through the shaft "40" to the beveled gear "27" on the shaft "18" then through the clutch members, to the pinion "29", and thence to the spur gear "14". 55 The spur gear in motion causes the pitman to reciprocate, thus moving the sector and thereby causing the dolly to rotate back and forth at the desired speed. The clutch members are employed for throwing the dolly 60 in and out of motion. The shifting of the clutches is accomplished by means of the shifting arm "32" in the groove "31" on the pinion "29". The arm "32", as before stated, is connected to the shifting rod "34". 65 This rod extends along the wringer frame

to a point on the opposite side, where it is pivoted to a crank "59" fixed on the end of a journaled roller "60" which roller is mounted on a bracket "61" on the wringer frame. By rotating the roller on which the 70 crank is fixed, it will be seen that the shifting rod will be moved back and forth a sufficient distance to cause the clutch members to engage and disengage. This movement is limited to keep the pinion "29" and spur gear "14" in mesh at all times. For rotating the roller "60" an arm "62" is employed. When the arm is in its upper position the clutch members are disengaged, and when moved to its lower position the clutch 75 members are moved to engagement. Thus, it is obvious that the dolly can be started or stopped independently, of the wringer, at the will of the operator. Another feature to be noticed in this connection is the arrangement whereby the shifting rod "34" 80 passes through the two sides of the casing where are formed long bearings for it to work in. This holds the rod in rigid position at the point where the arm "32" is attached and permits the pinion to be shifted with great ease and positiveness. Furthermore, this arrangement leaves the casing entirely closed at its bottom so that it can be 85 filled with grease for lubricating purposes. 90

For operating the wringer, it is of course understood that the shaft "18" is always in motion when the motor is running. The pinions "36" and "37" being fixed to the shaft, are of course continuously in motion. 100 With the gears in the position shown in Fig. 2, power is transmitted from the pinion "23" to the spur gear "13" which is fixed to the wringer shaft. This operates the wringer in one direction. For reversing, the 105 shifting mechanism before mentioned is employed.

The rod "26" is pivoted at its outer end to a lever "63", which lever extends through a slot "64" in a bracket "65" and is pivoted 110 to the bracket. Said bracket is in turn secured to the wringer frame. Three notches are provided in the lower edge of the slot for holding the lever in place, the notches at each side being designed to receive the lever 115 when the wringer is operated in either direction, and the middle notch being to receive the lever when the wringer operating mechanism is in neutral position. Thus, it will be seen that by moving the lever "63" to the 120 central notch the pinion "23" will be disengaged from the spur gear "13", while the pinion "21" will not be moved far enough to engage the spur gear "13". This will, of course, leave the wringer in its inoperative 125 position. Then, by moving the lever to its extreme outward position the pinion "21" will engage the spur "13" and cause the wringer to be operated in an opposite direction. It will be noted that by having the rod 130

enter at the center of the arm "25" a uniform force is exerted on each of the sliding pinions, and the operation is therefore made easier and more positive.

5 It will be noticed that I do not employ keys, square shafts, and the like, for shifting the gears in my device, but on the contrary all gears are either rigidly secured to the shafts or left free to slide or rotate independently of the shafts. This is especially desirable inasmuch as the keys and the like that are usually employed for sliding gears very frequently wear, thus casing unnecessary noise and loss of motion in the gearing 10 device.

Another feature is to be found in the convenient manner in which I have arranged the driving mechanism for the dolly. Here it will be seen that the driving pinion "29" 20 is at all times in mesh with the spur gear "14", and the operation of throwing the dolly in and out of motion is made easier inasmuch as the clutch members are capable of engagement much more easily and 25 readily than are gear wheels. The danger of stripping the gears is thereby entirely eliminated.

While I do shift gears in and out of mesh to operate the wringer, it will be understood 30 that the danger of stripping the gears in this case is not present inasmuch as the wringer is more easily operated and is moved at a considerably less speed than the dolly.

35 I desire to emphasize particularly the ingenious and simple manner by which the wringer is reversed, viz.—the sliding of two gears on separate shafts by one and the same lever. This arrangement greatly simplifies 40 the work of the operator.

On the whole my construction permits a compact arrangement of the working parts and a readily accessible location for the operating levers. The work of assembling is 45 greatly facilitated because of the fact that all of the important parts are contained in the one casing and there is not therefore any necessity for alining shafts or other intricate work requiring the services of a skilled mechanician.

50 It is to be understood that minor changes can be made in the details of construction without departing from the spirit of my invention.

55 What I claim therefore, and desire to secure by Letters Patent of the United States, is:

1. A gearing device of the class described, comprising in combination, a frame, a shaft 60 in said frame, a spur gear fixed to said shaft, three shafts circumferentially arranged below said spur gear, a loosely mounted pinion on the first one of said three shafts designed to mesh with said spur gear, a fixed pinion and a loosely mounted pinion

on the second of said three shafts, said fixed pinion being in mesh with the first-mentioned sliding pinion and the other pinion being designed to mesh with the spur gear, a fixed pinion on the third one of said three shafts in mesh with the fixed pinion on the 70 said second shaft, a fixed pinion on said third shaft in mesh with the loosely mounted pinion on said second shaft, means for sliding said loosely mounted pinions on their shafts to engage and disengage said spur gear, and means for imparting a continuous rotary motion to the third one of said shafts.

2. In a gearing device of the class described, the combination of a frame, a shaft on said frame, a spur gear fixed to said shaft, three shafts circumferentially arranged about said spur gear, a loosely mounted pinion on the first one of said three shafts designed to mesh with said spur gear, a fixed pinion and a loosely mounted pinion on the second one of said three shafts, the fixed pinion being in mesh with the first mentioned loosely mounted pinion and the 80 loosely mounted pinion being designed to mesh with said spur gear, a fixed pinion on the third one of said three shafts in mesh with the fixed pinion on said second shaft, a fixed pinion on said third shaft in mesh with the loosely mounted pinion on the second shaft, means for sliding said loosely mounted pinions simultaneously on their shafts, so that when one of said pinions is moved out 85 of mesh with the spur gear the other is moved in, and means for imparting a continuous rotary motion to said third shaft.

3. In a device of the class described, the combination of a frame, a shaft thereon, a spur gear fixed to said shaft, three shafts 95 circumferentially arranged about said spur gear, a loosely mounted pinion on the first one of said three shafts designed to mesh with said spur gear, a fixed pinion on the second one of said three shafts in mesh with the fixed pinion and loosely 100 mounted pinion on said second shaft, a loosely mounted pinion on said second shaft designed to mesh with said spur gear, fixed pinions on the third one of said three shafts in mesh with the fixed pinion and loosely 105 mounted pinion on said second shaft, means for sliding said loosely mounted pinions on their shafts to cause them to engage and disengage said spur gear, a bevel gear fixed to the end of said third shaft, a bevel pinion in 110 mesh with said bevel gear, a shaft for said bevel pinion, a bevel gear fixed to said bevel pinion shaft, a motor armature and a bevel pinion thereon in mesh with the last-named bevel gear, substantially as and for the purposes stated.

4. In a device of the class described, the combination of a wringer shaft, a spur gear fixed thereto, two shafts arranged below said spur gear parallel with said wringer shaft, 115

- a loosely mounted gear on each of said parallel shafts, having a hub formed thereon provided with an annular groove, an arm fitted into said groove, a shifting rod fitted into said arm a shifting lever therefor, and means for imparting opposite rotary motions to said loosely mounted gears.
5. In a device of the class described, the combination of a frame, a shaft thereon, a spur gear fixed on said shaft, two shafts circumferentially arranged about said spur gear parallel with the shaft thereof, a loosely mounted gear on each of said circumferentially arranged shafts designed to mesh with said spur gear, said loosely mounted pinions being offset, an arm between said hubs provided with concave ends to enter said grooves, a shifting rod fitted into said arm and extending outwardly 10 along said frame, a shifting lever pivoted to said rod and to the frame for moving said rod to thereby simultaneously shift said pinions in and out of mesh with said spur gear, and means for continuously rotating said 15 pinions in opposite directions.
6. In a gearing device, the combination of a frame, a shaft thereon, a spur gear on said shaft, three circumferentially arranged shafts about said spur gear, a loosely 20 mounted pinion on the first one of said shafts designed to mesh with said spur gear, a fixed pinion and a loosely mounted pinion on the second one of said shafts, said fixed pinion being in mesh with said loosely 25 mounted pinion first-mentioned, said second mentioned loosely mounted pinion being designed to mesh with said spur gear and offset from the first-mentioned one, said loosely 30 mounted gears being provided with hubs 35 having annular grooves formed therein at opposite points, an arm between said hubs provided with concave ends to enter said 40 grooves, a shifting rod having one end fitted into said arm and extending outwardly 45 along said frame, a shifting lever pivoted to said rod and to said frame for moving the rod to thereby shift said pinions, loosely-mounted, simultaneously in and out of mesh with said spur gear, fixed pinions on the 50 third one of said three shafts in mesh with the fixed pinion and loosely mounted pinion on said second shaft, and means for imparting a continuous rotary motion to said third shaft.
- 55 7. In reverse gearing for wringers, a driven gear, two offset gears slidably arranged on separate shafts in position to mesh with said driven gear, means for sliding said offset gears simultaneously, and

means for rotating said offset gears in opposite directions.

8. In reverse gearing for wringers, a driven gear, two oppositely rotating gears slidably arranged on separate shafts in positions to mesh with said driven gear, means for retaining said oppositely rotating gears in a relatively fixed position offset from each other, and means for sliding said gears.

9. In reverse gearing for wringers, a driven gear, two oppositely rotating gears slidably arranged on separate shafts in positions to mesh with said driven gear, and spaced apart in a lateral direction, and means for sliding said oppositely rotating gears to effect an engagement of either one with said driven gear or to position where said gears will occupy disengaged positions on opposite sides of said driven gear.

10. In reverse gearing for wringers, a driven gear, two offset gears slidably arranged on separate shafts in position to mesh with said driven gear, means for sliding said offset gears to effect an alternate engagement or disengagement of either one with said driven gear, and oppositely rotating gears in mesh with said offset gears and so arranged that a constant mesh is maintained between them.

11. In a wringer, the combination of a frame, a wringer shaft, a gear on said wringer shaft, two offset gears slidably arranged on separate shafts in position to mesh with said gear on the wringer shaft, means for imparting opposite rotatable movements to said slidable gears, an arm extending between said slidable gears for retaining them in a fixed relative position, a shifting rod secured to said arm and extending along the wringer frame, and a lever on said frame for moving said rod.

12. In a gearing device for wringers, the combination of a wringer shaft gear, two shafts arranged about said gear parallel with the axis thereof, a slidable gear for each of said shafts designed to mesh with said wringer shaft gear, means for rotating one of said shafts, a fixed gear on said rotatable shaft in mesh with the slidable gear on the adjacent shaft, and means for sliding simultaneously said slidable gears to permit them to alternately engage and disengage with said wringer shaft gear.
